CLAIM

The ornamental design for a baffle with slit ends, as shown and described.

DESCRIPTION

FIG. 1 is a top front left perspective view of a baffle with slit ends showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a top front left perspective view of an alternative embodiment of a baffle with slit ends;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof; and,

FIG. 14 is a bottom plan view thereof.

The baffle with slit ends is shown with a symbolic break in its length. The appearance of any portion of the article between the break lines forms no part of the claimed design. The broken lines are included for the purpose of showing environmental portions of the baffle with slit ends and form no part of the claimed design.
